MOLDING.

No. 17,131.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,131, dated February 22, 1887.

Application filed November 2, 1885. Serial No. 181,710. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Extending upon the surface of the molding in a longitudinal direction there appears a raised flat band, A. The opposite edges of said flat band are of like outline. Said outline consists in a straight portion, B, extending longitudinally the molding, and a curved

portion, C, these portions alternating along the edge. The curved portions C of one edge are opposite the straight portions B of the opposite edge.

I claim—

The design for a molding, substantially as herein shown and described, which consists in the raised flat band A, with alternating straight portions B and curved portions C appearing on both edges.

FREDERICK MANKEY.
